ROTARY LAWN MOWER WHEEL

Neill C. Woelffer, Racine, Wis., assignor to Jacobsen
Manufacturing Company, Racine, Wis.

Filed May 31, 1973, Ser. No. 365,437

Term of patent 14 years

Int. Cl. D12—15, 16

U.S. Cl. D12—135

F I G. 1

F I G. 2

F J G. 3

F J G. 4

FIG. 1 is a front elevational view of a rotary lawn mower wheel showing my new design;

FIG. 2 is a sectional view taken along the line 2-2 of FIG. 1;

FIG. 3 is a rear elevational view thereof; and

FIG. 4 is a top plan view thereof.

I claim:

The ornamental design for a rotary lawn mower wheel, substantially as shown.
